UNITED STATES PATENT OFFICE

141,171

DESIGN FOR A BOTTLE

Gilbert S. Gruber, Somerville, Mass., assignor to National Carton & Label Corp., Boston, Mass., a corporation of Massachusetts

Application February 16, 1945, Serial No. 117,996

Term of patent 7 years

(Cl. D58—6)

To all whom it may concern:

Be it known that I, Gilbert S. Gruber, a citizen of the United States residing at Somerville, in the county of Middlesex and State of Massachusetts, have invented a certain new, original, and ornamental Design for Bottle, of which the following is a specification, reference being had to the accompanying drawing, forming part thereof.

In the drawing,

Fig. 1 is a plan view of a bottle showing my new design;

Fig. 2 is a front elevation of the bottle as shown in Fig. 1; and

Fig. 3 is an elevation taken at an angle of 60° with respect to Fig. 2.

The shape of the bottle is that of a regular octahedron.

I claim:

The ornamental design for a bottle, substantially as shown and described.

GILBERT S. GRUBER.
